UNITED STATES PATENT OFFICE.

JOHN FREMONT FREY, OF INDIANAPOLIS, INDIANA.

SEMICYLINDRICAL-STEREOTYPE-PLATE TRIMMER.

1,027,833.

Specification of Letters Patent. Patented May 28, 1912.

Application filed May 19, 1911. Serial No. 628,330.

To all whom it may concern:

Be it known that I, JOHN FREMONT FREY, a citizen of the United States, residing at Indianapolis, in the county of Marion and 5 State of Indiana, have invented a new and useful Improvement in Semicylindrical-Stereotype-Plate Trimmers, of which the following is a specification.

There is at the present time upon the market a machine, known as an automatic curved stereotype plate finishing and cooling machine, which is so designed as to receive curved stereotype plates from the casting box, trim the same ready for placing in 15 the press, and properly cool it for transference to the press. Such an apparatus is eminently successful if sufficient time is allowed to elapse between the pouring of the metal and its transference to the machine 20 in question but if, under stress of hurry incident to a special edition, or otherwise, the operators remove the plates from the casting box and begin manipulation thereof in the machine in question at too early a 25 period, I have found that a large percentage of loss occurs.

The object of my present invention is, therefore, to provide an attachment to or improvement of the said machine in order 30 to overcome this difficulty and thereby materially increase the speed at which complete stereotype plates may be produced and delivered to the press room.

The accompanying drawings illustrate my 35 invention.

Figure 1 is a perspective view of the above mentioned machine equipped with my improvements; Fig. 2 a fragmentary horizontal section showing my improvements; 40 Fig. 3 a transverse section through the trimmer head, and Fig. 4 an axial section of one of my attachments.

In the drawings, 10 indicates the main body of the machine to which reference has 45 been made. This machine comprises a saddle 11 having a semicylindrical delivery end 12 which is machined to fit snugly the stereotype plate 20. Arranged upon opposite sides of the saddle 11, in front of the portion 12, are horizontal guide surfaces 13, 13, which deliver to rotating milling cutters 14, 14, which are so arranged as to trim the opposite axial edges 15 of the stereotype plate. The plate is driven by hand over 50 the cutters 14 along the saddle 11 and, by 55 the portion 12 is guided into the trimmer

head 16 in which the plate is trimmed and properly chamfered at its ends. From this head the plate is delivered to the cooling chamber 17. Thus far the structure is 60 one commonly in use and I have found that in the operation of such a structure if I take a plate from the casting box too soon so that the metal is not firmly set, although still apparently of sufficient hardness, there will 65 be a slight sagging of the plate on the saddle and a consequent very slight outward expansion of the edges or ends of the semi-cylinder so that, when the plate is projected into the trimmer head, the type faces of a 70 few of the type lines immediately adjacent the edges of the plate will contact with the inner face of the trimmer head in such manner as to become scratched and so marred as to ruin the plate for use. This expansion or 75 sagging of the plate is very small indeed, but, as will be recognized, a difference of one-hundredth of an inch or even less in the height of the type is very appreciable in the printed result.

In my operation of a machine of this class, I have discovered that all possible injury of the plate in the manner described may be avoided in the following manner: Upon the receiving end of the trimmer head, at diametrically opposite points relative to the guide 12, I firmly clamp a bracket 25 which, at its inner end, carries a roller 26, the axis of which is at right angles to the axis of the saddle 11 and the plate 20. The 80 roller 26 is formed of any suitable cushion material, such, for instance, as leather, hard felt, etc., of such character that, while it is capable of exerting a very firm clamping force upon the plate, it will, nevertheless, be 85 so yielding as to accommodate itself to the type face of the plate without marring the type. The brackets 25 are bolted to the trimmer head 16 by bolts 27 or otherwise, 90 said bolts preferably passing through slots 28 in the bracket so that the rollers 26 may be accurately adjusted relative to the saddle guide 12. The brackets, of course, might be backed up by heavy springs but these are not at all necessary and, therefore, I prefer 95 to omit them. In practice, I have found that with this attachment I am able to take the plates from the casting box much sooner than heretofore and yet run them through the machine without danger of loss by 100 scratching, whereas heretofore it was not 105 at all unusual to lose as high as forty per 110

cent. of the plates because of too great hurry on the part of the operators.

I claim as my invention:

The combination with a curved stereotype plate trimmer comprising a receiving saddle and a trimmer head adjacent the saddle and into which a stereotype plate is to be projected, of a pair of rollers separate from the trimming mechanism and arranged adjacent the saddle and receiving end of the trimmer box upon opposite sides of the saddle, each of said rollers having a yielding

face arranged to act upon the type face of the plate as it enters the trimmer head to prevent spread of the edges of the plate 15 without marring the type faces.

In witness whereof, I have hereunto set my hand and seal at Indianapolis, Indiana, this 16th day of May, A. D. one thousand nine hundred and eleven.

JOHN FREMONT FREY. [L. S.]
